1

The present invention relates to a lock chamber used for navigation purposes and serving for raising or lowering of floating vessels from one water level to another.

It is an object of the invention to provide a lock chamber working without loss of water and requiring no mechanical means for raising of the floater used for this purpose. A further object of the invention is to speed up the passage of vessels through the lock chamber.

Lock chambers having floaters and pressure devices are known per se, they are however requiring always the same difference of water levels and are needing for the movement of the floaters mechanical driving means and a constant force during the whole lifting of the floaters. Moreover the use of packing for the by pass tube with regard to the floater is unsuitable as the floater requires a free movement in all directions.

Other known chambers of this kind using compressed air or air of reduced pressure are transferring the water from the chamber proper into the floater or in the opposite way and it is necessary that its content is equal to the content of the chamber or in an other embodiment to have twice the content of it.

According to the invention the floater does not need to be lifted during the whole upward movement and its content is not dependent upon the content of the chamber.

Some embodiments of the invention are presented in the accompanying drawing where:

Fig. 1 is showing schematically a simple one floater lock chamber in sectional view prepared for raising of a ship.

Fig. 2 a similar view with the chamber prepared for lowering of a ship.

Fig. 3 a sectional view of a lock chamber with two floaters.

Fig. 4 the same view of a double lock chamber with two floaters.

Fig. 5 a longitudinal sectional view of a stepped up lock chamber.

Fig. 6 is a sectional view of a floater lock; and

Fig. 7 is a plan view of a floater lock.

Referring to Figs. 6 and 7 of the drawings, a lock chamber K is disposed intermediate an upper basin N and a lower basin N'. Lock gates V_h and V_d separate the lock chamber K from the upper and lower basin, respectively. In the lock chamber K a floater P is arranged.

The area of the water surface taken up by the floater, and the volume of this floater is comparatively very large, in a preferred embodiment of the present invention the area of the horizontal

2

cross-section of the floater is two thirds of the area of the lock chamber. The ship which is to be raised or lowered is floating in the area of the lock chamber outside of the floater. When the floater is immersed by means which will be explained later on in detail, the water level in the lock chamber is raised and with it the ship floating on the water contained in the lock chamber outside of the floater. When the floater is raised to a higher position by means which will be explained in detail later on, the water level in the lock chamber outside of the floater drops to a lower level. Consequently by immersing, or raising the floater, the water level in the lock chamber is raised, or lowered, respectively, as desired.

Supposing that the total area of the lock chamber is F and the area of the floater $\frac{2}{3}F$, an immersing of the floater for a distance h below the lower water level will displace a volume of water $\frac{2}{3}hF$. This volume of water will be displaced into the adjacent area of the lock chamber where the ship is floating and will raise the water level there above the lower water level for a distance of $2h$, since the area of the lock chamber outside of the floater is half the area of the floater, i. e. $\frac{1}{3}F$.

Since the floater is immersed now for a distance h below the lower water level and the water level in the lock chamber has been raised above the lower water level for a distance $2h$, the minimum height of the floater is $3h$ if the floater is not to be immersed with its top below the higher water level.

The height of the floater being at least $3h$ and the difference between the lower and the higher water level in the lock chamber being $2h$, the height of the floater in the described arrangement is substantially 1.5 times the difference between the higher and the lower water level in the lock chamber.

The immersing of the floater is affected by filling it with water, and it is raised by compressed air.

With reference to Figs. 1, 6 and 7 a lock chamber K is first arranged, which may be alternately opened to the upper or lower water basin, the upper basin N having the water level h_{uv} , the lower basin (not shown on this figure), the water level spv . In the position shown on Fig. 1 the lock chamber K may be connected with the lower water basin. A floater P is arranged within the lock chamber K, the upper part O of which, open in the upward direction, may be called the water space, the lower part O₁, open downward

the air space. The upper part O is connected by means of a pair of telescopic tubes *a*, *b*, with the upper basin N, the tube *a* being rigid with the floater P, the tube *b* stationary in the masonry of the lock chamber. Both tubes are provided with double walls so as to form annular spaces between them to seal the water and air space of the floater P from the water of the lock chamber. The floater P may thus perform a raising or lowering movement within the lock chamber K. A flexible hose V₂ is further provided to connect the air space O₁ of the floater P with the compressed air supply or with the air outlet alternatively. The tube *b* is bent and continues within the upper basin N in a telescopic tube C, which may be raised above the upper water level *hv* of this basin.

Let us suppose that a ship should be raised from the lower water level *spv* to the upper water level *hv*. It enters the lock chamber K in the space between the wall of the lock chamber K and the floater P, whereas the lock gate of this chamber (not shown) is closed. The air hose V₂ is thereafter connected with the air outlet enabling the air in the air space O₁ to escape and the floater P to sink. Simultaneously, the telescopic tube C is raised above the high water level *hv* to prevent a too quick filling of the water space O of the floater from the upper basin N (see Fig. 1'). The floater sinks as the air space O₁ is decreasing down to the O₁ shown on Fig. 1. The telescopic tube C is then lowered with its end below the level of the upper basin N enabling water to flow through tubes *b* and *a* to the water space O causing thus a further sinking of the floater P. Fig. 1 shows the floater in an intermediate position, the space O partly filled with water and the level in the lock chamber K somewhat raised. If the free floor space of the lock chamber K and the floor space of the floater are in a proportion of 1:2, the sinking of the floater P for a certain height causes the raising of the water level in the lock chamber K for the double of it. The air space of the floater is thereby further compressed to the amount O₁^{II}. Fig. 1 shows the final stage, with the water levels of the upper basin N and of the lock chamber being equal and the gates of the lock chamber may be opened to admit the ship to the upper basin.

The opposite procedure is used for lowering a ship from the upper to the lower water level. With the lock gates closed and the telescopic tube C raised above the water level of the upper basin, compressed air is admitted into the air space O₁ of the floater P, which raises to a certain extent until the air occupies the space O₁^{IV} shown in Fig. 2. The supply of compressed air is then stopped and the lock gates closed. The telescopic tube C is then lowered bringing its end below the level of the water in the water space O of the floater P allowing water flow through this tube from the water space O into the basin N (see Fig. 2). The speed of the flow of the water is regulated by the height of the telescopic tube C. The air in the air space O₁^{IV} expands when the water space O is emptying causing a further raising of the floater P and a lowering of the water level in the lock chamber until the original state shown in Fig. 1 is attained.

Thus, no water is lost during the whole performance of the raising or lowering of the ship and only a comparatively small power is required as the raising of the ship takes place due to the floater being lowered when filled with water from

the upper basin and the lowering is done by raising the floater for an amount allowing water to flow back to this basin.

The use of the telescopic tube C is advantageous for a better control of the speed of the flowing water and of the height of the water levels. It is obvious that the device would work without this tube being extended beyond the water level of the upper basin, the control of the water flow and water level would be however not so convenient.

Fig. 3 shows a double floater lock chamber acting in a similar way. The floater I is situated within the lock chamber similar as in Fig. 1, the floater II is in the lower basin. The air space of the floater I does not communicate with any air supply or outlet, the air space of the floater II is controlled in a way similar to that of the floater according to Fig. 1. The water spaces of both floaters are connected by the tubes T, T₁, T₂, provided with water seals.

The height of the water level of the lock chamber V is controlled by admitting or releasing air into or from the air space of the floater II. In the position shown on Fig. 3, the water level in the lock chamber V is raised to the level *hv* of the not shown upper basin. By releasing air from the air space of the floater II this floater sinks and allows water from the floater I to flow through the tube T into the floater II. The air compressed in the air space B₁ expands thereby and lifts the floater I simultaneously until sufficient water has overflowed from the floater I to floater II so that the floater I is raised to such an extent as to lower the water level in the lock chamber V to the height *spv* of the lower water basin.

By admitting compressed air into the air space B₁ of the floater II, the flowing back of the water from floater II to floater I is achieved by simultaneously raising the level of the lock chamber V until the water level *hv* of the upper basin is reached.

Fig. 4 shows a double lock chamber with floaters in each of them. Both floaters are alike and their water spaces connected by the telescopic tubes T₃, T₄. The air spaces B₁ are both connected by tubes not shown with valves for admitting of compressed air or for releasing air into the surrounding space. Both lock chambers are involved during one performance, the water from the water space of one floater being brought to the water space of the other floater by releasing air from the air space of one floater and admitting of compressed air into the air space of the other floater. This arrangement is the most economical from the point of view of power consumption.

Fig. 5 shows a stepped up lock chamber used in cases of greater differences of water levels. The said figure is a sectional view through both chambers and the upper and lower basin with the floaters and the corresponding recesses for their operation behind. The difference of water levels of both basins is divided into two equal heights S₁ overcome each by one of the lock chambers. A floater I'' having an upper water space and a lower air space similar to that in Fig. 1 is arranged within the upper lock chamber, the cross section of which corresponds to that shown in Fig. 1. A similar floater II'' is provided within the lower lock chamber having however between the water and air space an additional hermetically sealed air space D of the height S₁. Both water spaces are again communicating by means

of the tubes T_5 , T_6 , T_7 and both air spaces are connected to valves for admitting of compressed air and releasing of air into the surrounding space. The lock chambers are provided with doors U_h , U_s , U_d enabling their alternative interconnecting or connecting with the upper or lower basin. The whole construction and performance is but for the additional hermetically closed air space D similar to that of the double lock chamber in Fig. 4. The additional air space D provides for the different height of both lock chambers. In the position shown in Fig. 5, the upper lock chamber is prepared for admission of a ship from the upper basin. At closed doors of the lock chambers compressed air has been admitted to the lower air space of floater II'' , raising this floater somewhat, so that the water level of its water space is higher than that of the floater I'' . Simultaneously the air space of the upper floater I'' is opened into the surrounding space. Water from the floater II'' flows through the tubes T_8 , T_7 , T_6 into the water space of floater I'' , which is lowered and displaces the water contained in the upper lock chamber so that its level rises up to the level of the upper basin, after which the gates U_s may be opened. In an analogous way the level in this lock chamber is lowered, and equally the level in the lower lock chamber.

The arrangement according to the invention does not require any water from the upper basin so that it is especially suitable for canals, which have either no or only a poor water supply. It equally enables a very quick performance as no water is admitted into the lock chambers and the raising of the water level is solely achieved by displacing the water in the lock chamber by a floater. The speed of raising of the water level may be therefore considerably increased as the water is displaced along the whole length of the chamber causing no whirling or currents. The power required for the displacing of the water is comparatively small as the water is in fact not lifted but solely displaced, so that only the difference of water levels required for an overflow of the water from one space to another must be provided.

I claim:

1. A floater lock system of the character described, including the combination, with a stationary lock chamber in which the water level is to be altered, of at least one additional stationary chamber or basin disposed adjacent to the lock chamber; fixed means separating the two chambers; a floater partly immersed in water in the stationary lock chamber and having a downwardly open air chamber and a separate upwardly open water chamber; and interconnecting conduit means extending between both stationary chambers and connected at one end to the water chamber in the floater and extending with the other end thereof into the additional stationary chamber or basin for emptying the water chamber of said floater into or filling it from said additional stationary chamber or basin.

2. A floater lock system of the character described, including the combination, with a stationary lock chamber in which the water level is to be altered, of at least one additional stationary chamber or basin disposed adjacent to the lock chamber; fixed means separating the two chambers; a floater partly immersed in water in the stationary lock chamber and having a downwardly open air chamber and a separately upwardly open water chamber with upwardly open adjustable means partly immersed in water in

the additional stationary chamber or basin; and interconnecting stationary conduit means between both stationary chambers connected to the water chamber in the floater and extending into the upwardly open adjustable means in the additional stationary chamber or basin for emptying the water chamber in the floater into and filling it from said upwardly open adjustable means in said additional stationary chamber or basin.

3. A floater lock system of the character described, including the combination, with a stationary lock chamber in which the water level is to be altered, of at least one additional stationary chamber or basin disposed adjacent to the lock chamber; fixed means separating the two chambers; a stationary conduit extending between the two stationary chambers and having the ends thereof projecting individually upward and opening upward in said stationary chambers; a floater partly immersed in the lock chamber and having an open top and an open bottom and surrounding the one upwardly extending end of the conduit located in said lock chamber; an intermediate water tight partition fixed in the floater and having an aperture and therein separating the interior into an upwardly open water chamber and a downwardly open air chamber; a water sealed connection between said one upwardly extending end of said conduit and the aperture in said partition allowing free vertical movements of said floater in said stationary lock chamber; an upwardly open means vertically movable in the additional stationary chamber or basin; and a water sealed connection between the upwardly extending end of said conduit in said additional stationary chamber or basin and said upwardly open means allowing vertical movement of the latter in said additional stationary chamber or basin to expose the upper end of said upwardly open means above the water level in the latter chamber.

4. A floater lock system of the character described, including the combination, with a stationary lock chamber in which the water level is to be altered, of at least one additional stationary chamber or basin disposed adjacent to the lock chamber; fixed means separating the two chambers; a stationary conduit extending between the two stationary chambers and having the ends thereof projecting individually upward and opening upward in said stationary chambers; a floater partly immersed in the lock chamber and having an open top and an open bottom and surrounding the one upwardly extending end of the conduit located in said lock chamber; an intermediate water tight partition fixed in the floater and having an aperture therein and separating the interior into an upwardly open water chamber and a downwardly open air chamber; a water sealed connection between said one upwardly extending end of said conduit and the aperture in said partition allowing free vertical movements of said floater in said stationary lock chamber; a second floater partly immersed in water in the additional stationary chamber or basin having a downwardly open air chamber and an upwardly open water chamber; a partition in the second floater separating the air chamber from the water chamber therein; the partition in said second floater having an aperture therein; and a second water sealed connection between the latter aperture and the upwardly projecting end of the conduit located in said additional stationary chamber or basin, said conduit serving to empty the water chamber of the first men-
